TROLLEY SWITCH

Jed F. Woolley, Jr., and Lawrence J. Long,
Salt Lake City, Utah

Application October 25, 1930, Serial No. 491,099

2 Claims. (Cl. 191—38)

Our invention relates to a trolley system and has particular reference to an overhead switching system for (A) trolley cars or (B) busses in which one or more overhead conductors are employed.

One object of our invention is to provide a system in which the overhead switches or frogs at a turn-out may be automatically controlled by the operator on a moving vehicle to either 10 the "straight-ahead" or "turn-out" position.

Another object is to automatically set the switches to either the "straight-ahead" or the "turn-out" position independently of the operator on the vehicle.

15 Other objects of our invention will be disclosed in the specification as the description of our invention proceeds.

Our invention resides in the new and novel construction, combination, relation of parts and 20 circuit connections described in the specification and shown in the drawings accompanying the specification.

In the drawings:—

Fig. 1 is a schematic drawing of our system 25 showing the mechanism positioned to guide the current collectors of a vehicle, either a trolley car or a trolley bus, moving toward the left, to the branch or turn-out conductor.

Fig. 2 shows more in detail the main operating switch and mechanism.

Fig. 3 shows the automatic contact device in section for automatically setting the switches to the "turn-out" position when engaged by a current collector.

35 Fig. 4 is a partial sectional view showing in detail the spring toggle for maintaining the switch tongue in either of its two positions.

Fig. 5 is a schematic drawing of a modification of our system shown in Fig. 1 and in which 40 separate electrically operated means is used to operate the switches.

In the system shown and herein described we employ switch pans 1 and 2 which may be similar to that shown in Matthes Patent 1,682,136 45 dated August 28th, 1928 and comprising a body member 3 with the straight-of-way guides 4 and 5 and the turn-out guide 6. These guides receive the trolley conductors and hold them fixed with respect to the switch pan and also 50 guide the current collector onto and off of the pan. At the inner end of the turn-out guide 6 is secured a tongue 7 pivoted to the body 3 by the stud 8 which is fixed to the tongue 7 and passes through the body 3. The body 3 is provided with longitudinal flanges 9 and 9' which

are spaced and project downwardly. The pans are supported by the trolley wires and in addition thereto by cables passing through the eyes 39 thus permitting the switch to yield vertically.

60 Fixedly secured to the pivot 8 is a bell crank having arms 10 and 11. Pivotedly secured to the free end of the arm 11, which may be a clevis or tongue, by means of the pin 12 are two telescopic members 13 and 14 biased to their extended position by means of the spring 15. The exposed end of the member 14 is provided with a transverse passage to receive a pin 16 to pivotally secure the member 14 to the pan member 3.

65 Referring to Fig. 2 it will be seen that when the axes of the members 11, 13 and 14 are in a straight line between the pivotal centers 8 and 16 that the members 13 and 14 will be in their retracted position and the spring 15 will be under its maximum compression, but when the axis of 70 the member 11 is out of alignment with the axes of the members 13 and 14, the pivot 12 will be out of alignment between the pivots 8 and 16 and the spring 15 will exert a pressure upon the parts 13 and 14 tending to maintain the pivot 12 off center with respect to the pivots 8 and 16 thus yieldingly holding the members 10 and 11 in either of two positions with respect to the center line passing through the pivots 8 and 16 and likewise holding the tongue 7 in either of two 75 positions as represented by the numerals 7 or 7'.

80 In Fig. 1 we have shown switches 1 and 2 held together by means of rigid spacing bars 17 which may preferably be made of wood secured to the switches 1 and 2 and holding them in rigid, insulated relation. The switch tongue 7 of the pan 2 is provided with an operating lever 18 which is connected to the pivotal end of the lever 11 by means of the insulated connecting rod 19 so that the tongues on the two switches act in unison 95 and alike.

85 One of the switches as for instance, switch 1 is provided with electrically controlled mechanism for operating the switches and may comprise a coil 20 which when energized will move the plunger 21 to the left and with it the lever 10 which in turn moves the switch tongues to the turn-out position as shown by the tongues 7 in Fig. 1. When the coil 22 is energized the plunger 21 is moved to the right thus moving the switch 105 tongues to the position shown by 7' permitting the current collectors to pass straight through the switches.

100 In order to further control the operation of the switches we employ a contactor 23 which may 110

- be constructed along the lines of the device shown in Stolp Patent 1,480,968 dated January 15th, 1924, or the device may consist of an elongated wood insulating bar 24 shown in section in Fig. 3 together with two metal angle bars 25 and 26 secured thereto by means of the bolts 27. The length of the contact bars 25 and 26 is made of such length to give sufficient time for the energization of the coil 20.
- 10 The contact device 23 is also provided with contact plates 25 and 26 and we prefer to construct the same such that the trolley wire 28 is so positioned that the current collector will not contact with the trolley wire throughout its entire passage across the contact device, but the contactor will engage with the plates 25 and 26 as shown in Fig. 3. This construction assures one that the collector will positively engage the contacts 25 and 26 and connect the conductor 30 to the trolley wire. One contact 25 is electrically connected to the trolley wire 28 by means of the conductor 29 and the other contact plate 26 is connected to one end of the coil 20 by means of the conductor 30. The other end of the coil 20 is connected to the trolley wire 31' by means of the conductor 32.
- 15 It will be evident that if the trolley wire 28 is positive as we prefer to make it and the trolley wire 31 and its continuation 31' is negative that when the current collector 33 electrically connects the contact bars 25 and 26 as the vehicle moves from right to left, current will flow from the trolley wire 28 through the conductor 29 and trolley wheel from contact 25 to contact 26 thence through the conductor 30, coil 20 and conductor 32 to the negative trolley wire 31' thus energizing the coil 20 and moving the plunger 21 to the left if not already in that position and setting the switch tongue to the position shown by the numeral 7 in both switches. It will be evident that this operation will be automatic and take place irrespective of whether the car operator has his controller set for the "off" or "on" position.
- 20 30 As soon as the controller passes beyond the contactor 23 the circuit to the coil 20 will be broken, but the tongue will remain in its last moved position through the medium of the spring toggle described above. The switch is now set for the current collectors 33 and 33' on the vehicle to take the turn-out trolleys 28'' and 31'' respectively.
- 25 It will be apparent that a car approaching the switch from the right will automatically set the switches for a turn-out position and consequently the motorman will know that the switch is so set. In order that the motorman may operate the switch to the "straight ahead" position if he so desires we provide an insulated contact 34 between the insulators 35. Contact 34 may be of wire or bar and made of any length desired and its ends are entirely disconnected from the trolley conductor 28. Leading from the contact 34 is a conductor 36 connected to one end of the coil 22 and the other end of the coil 22 is connected to the trolley 38 by the conductor 37. It will be seen that the coil 22 is so arranged that whenever current is drawn from contact 34, such current will all pass through the coil 22. The vehicles are equipped with electric motors M and when operating the current flows from the positive trolley 28 through the controller C on the vehicle thence through the motors and then to the negative trolley 31 (B, Fig. 1) or to ground (A, Fig. 1). The operation of the motors is

under control of the vehicle operator. When one of the current collectors on the vehicle engages the contact 34, the vehicle operator may energize or de-energize coil 22 as he may see fit by either throwing his motor controller to the "on" position or the "off" position. The flow of current with the controller "on" is as follows: from the trolley 28 through the conductor 37, coil 22, conductor 36, contact 34, then through the controller and motors on the vehicle to the negative trolley 31 (B, Fig. 1) or to ground (A, Fig. 1).

80 85 When the coil 22 is sufficiently energized the plunger 21 will be drawn to the right and this will transmit motion to the tongues on the switches to move them in unison to the position shown as 7. This leaves the switches in a position for conducting or guiding the current collectors 33 and 33' there-across from trolleys 28 and 31 to trolleys 28' and 31' respectively between the tongues 7' and flanges 9. The switch tongues will be held in their 7' positions through the medium of the spring toggle. A vehicle following another vehicle will automatically change the position of the tongues from 7' to 7 when its collector engages the contact 23 and the vehicle operator knowing this has only to bear in mind whether he desires to go straight through the switches or take the turn-out and in the former case he applies power to his motors as the collector 33 passes across contact 34 and to take the turn-out or branch he passes across contact 34 with power "off" as his collector has previously automatically set the switch tongue to the position 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 tor and likewise the engagement of the controller with the contact 23 would set the switch tongues for straight-of-way operation in place of the branch operation shown.

5 Since the coil 20 is connected directly across the positive and negative conductors we construct the coil 20 with a much higher resistance than that of coil 22, thus the circuit from contact 23 through coil 20 to trolley wire 31' is greater than 10 that of the circuit from contact 34 through coil 22 to trolley wire 28.

From this description it will be quite evident 15 that the system is quite flexible as to changes which may be made, but all of which will still fall within the scope of our invention, therefore we 15 wish to be limited only by our claims.

We claim:—

1. In an electrically operated trolley guide for use with a pair of spaced trolley wires of opposite 20 polarity and one wire grounded, in combination, a trolley switch having a pair of spaced switch pans connected by transversely disposed and spaced insulating means attached to the body of the pans adjacent their ends to hold the pans in 25 fixed and insulated relation and having means on the pans to secure the trolley wires thereto also a plurality of means on the switch for the attachment thereto of steady cables and each pan having a switching tongue pivoted thereto to guide 30 the current collectors mounted on moving vehicles and insulated means associated with the tongues to operate them in unison to different positions, the switch also having electrically operated mechanism supported above and by the 35 pans to actuate the tongues and having a pair of energizing coils of substantial difference in resistance acting upon a single plunger associated with the tongues and insulated operating means, each coil having one end permanently connected to one 40 of the two trolley wires but not the same wire; a contactor having a surface alignment with that of the adjacent trolley wire and connected to the coil which has one end connected to the said adjacent trolley wire and insulated therefrom except 45 through the said coil whereby the coil is energized either when the contactor alone or the contactor and the trolley wire of opposite polarity are simultaneously engaged by current collectors with "power on" the motors to move the tongues to a 50 predetermined position but which coil is not energized sufficiently to operate the tongues when the contactor is engaged by the current collector with "power off" the motors, a second contactor

connected to the other coil and insulated from the trolley wire except through the said coil connection whereby the coil is energized whenever the contactor is engaged by a collector on the moving vehicle either with or without "power on" to move the tongues to a predetermined position before the collector engages the first said contactor.

2. In an electrically operated trolley switch for use with spaced trolley wires of opposite polarity, in combination, a trolley switch having a pair of spaced trolley pans and spaced means for holding the pans in a fixed spaced and insulated relation, means on the switch to secure the trolley wires thereto to yieldably support the switch, a movable tongue pivotally mounted on each pan to guide the current collector on the trolley of a moving vehicle, means to connect the tongues in insulated relation and operate them simultaneously, electrically operated mechanism supported by the pans and having a pair of operating coils with a substantial difference in resistance to operate the mechanism to different positions when the coils are energized, the mechanism being associated with the tongues and their connecting means to actuate the tongues to their different positions; a contactor having a contact bar and means to attach the bar in aligned and fixed and spaced relation to one of the trolley wires, the said attaching means secured to the ends of the trolley wire which are adjacent the ends of the contact bar, the end of one coil connected to the contact bar and the other end connected to the said trolley wire whereby the coil is energized either when the 100 contactor alone or the contactor and the trolley wire of opposite polarity are simultaneously engaged by current collectors with "power on" the vehicle to move the tongues to a predetermined position, a second contactor having a bar connected to the other coil and insulated from the trolley wire except through the said coil which is connected to the other trolley wire whereby the coil is energized whenever the contactor is engaged by a collector on the moving vehicle 105 either with or without "power on" the vehicle to move the tongues to a predetermined position prior to the collector engaging the first said contactor and insulating means to hold the last said contact bar in fixed relation to the trolley 110 wire.

JED F. WOOLLEY, JR.
